ADJUSTABLE JAMB

Louis Morris, Jr., Rehoboth, Mass., assignor of fifteen percent to John F. Penkala, Warren, and fifteen percent to Arthur Tavares, Bristol, R. I.

Application February 7, 1956, Serial No. 564,019

6 Claims. (Cl. 20—12)

The present invention relates generally to door frames and the like and more particularly to an adjustable jamb therefor.

A primary object of the instant invention is the provision of an improved adjustable door jamb for the purpose of readily enabling a proper fit to be made with the striking edge of the door in cases where the door has either shrunk or swollen beyond its original size when first fitted and hung within the door frame.

Another object of the instant invention is the provision of an adjustable jamb which may be readily adjusted by an ordinary screw driver or the like without the necessity of disassembling any of the door frame structure.

Another object is the provision of an improved adjustable jamb so constructed and arranged as to provide maximum resistance against surreptitious and unauthorized breaking open of the door.

A further object of the instant invention is the provision of an adjustable jamb having novel and improved weatherstripping characteristics.

Still another object of the instant invention is the provision of an adjustable door jamb so constructed and arranged as to make it possible to mount and remove the trim overlying said jamb from the outside without the necessity of any disassembling.

A further object is the provision of an adjustable jamb that will not deter from the attractiveness of the door frame in which it is mounted, no matter what its position of adjustment may be.

Another object is the provision of an adjustable jamb that is both simple and efficient in operation through a relatively wide range of adjustment but which nevertheless is commercially feasible to manufacture.

Other objects, features and advantages of the invention will become apparent as the description thereof proceeds when considered in connection with the accompanying illustrative drawings.

In the drawings which illustrate the best mode presently contemplated by me for carrying out my invention:

Fig. 1 is a front elevation of a door and frame assembly embodying the instant invention;

Fig. 2 is an elevational section, on an enlarged scale, taken on line 2—2 of Fig. 1;

Fig. 3 is a fragmentary front elevation, on an enlarged scale, with portions broken away to more clearly show the adjustable jamb structure;

Fig. 4 is an enlarged fragmentary section taken on line 4—4 of Fig. 1, with the door per se removed in order to more clearly show the parts;

Fig. 5 is an enlarged fragmentary section taken on line 5—5 of Fig. 2; and

Fig. 6 is an enlarged fragmentary section taken on line 6—6 of Fig. 2.

An ever increasing problem in the construction of homes and other building structures has been the binding and jamming of doors during the closing thereof due to shrinkage or swelling of the surrounding frame structure or the door itself. This problem has become particularly

2

troublesome in recent years in view of the great demand for new homes and the like thereby necessitating the use of streamlined building procedures in order to keep up with this increasing demand for production. As a result of these streamlined procedures, it is often necessary to utilize wood which is not properly aged and which, due to this fact, is very susceptible to shrinkage and expansion when coming in contact with varying atmospheric conditions. As a result of the foregoing, it has become desirable to provide a door frame structure comprising a movable jamb which may be readily adjusted to compensate for such shrinkage and swelling subsequent to the mounting of the door.

Movable and adjustable jambs have been utilized heretofore, but in the past certain disadvantages have been inherent in their construction, which disadvantages rendered said prior art adjustable jambs unfeasible from a commercial standpoint. More specifically, since an adjustable jamb usually carries thereon the keeper plate which operates with the door latch and lock, it is imperative that said jamb have sufficient strength when mounted to resist an outward thrust or pull on the door when the latter is in locked condition. It is further imperative that the movable jamb be readily adjustable from an accessible position. Another disadvantage of prior art movable jambs has been the problem of providing adequate weatherstripping between said jamb and its associated door structure, while still another problem has been the lack of a structural design which would enable the trim strip which covers the adjustable jamb to be easily mounted in position, and disassembled when desired, without the necessity of disassembling the entire structure.

Accordingly, there is provided by the invention now to be described an adjustable jamb structure which overcomes these aforesaid disadvantages. It will be understood that while the adjustable jamb is preferably mounted adjacent to the striking edge of its associated door, said structure could well be mounted on the hinge edge frame of the door. In the latter design, the hinges would be mounted directly to the adjustable jamb. The invention is not affected by the specific location of the adjustable jamb, and hence for purposes of illustration, my invention has been illustrated and will be described with respect to an adjustable jamb located adjacent the striking edge of its associated door.

Since the problem toward which this invention is directed is most prevalent in connection with outside doors, where atmospheric conditions are most likely to have a pronounced effect, my invention now to be described is directed to the construction of such an outside door. It will be understood, however, that the principles of my invention are equally applicable to inside doors as well.

Referring now to the drawings, and more particularly to Fig. 1 thereof, there is shown a door frame structure comprising a door 10 hingedly mounted as at 12 in a manner well known in the art and having a handle 14 which has associated therewith conventional latching means (not shown). Trim strips 16, 18 and 20 and threshold 22 surround the doorway in a well-known manner.

The adjustable jamb structure constructed in accordance with the instant invention is shown most clearly in Figs. 2 through 6 and comprises a stationary jamb 24 and a movable jamb 26. As will be seen most clearly from Figs. 5 and 6, the inner edge of the stationary jamb 24 is offset with respect to the movable jamb 26 whereby to provide a stop means 28 for limiting inward movement of the door. It will further be noted that jambs 24 and 26 are in side-by-side relation with respect to each other, and at their contacting edges are provided with interengaging offset portions 30 whereby to provide weatherstripping means therebetween.

Jambs 24 and 26 comprise elongated beams, preferably of wood, and are mounted between the outer house wall 32 and trim strip 20, which forms a part of inner house wall 34, the latter having mounted thereon the trim strip 20 in a manner hereinafter to be described in detail. As will be seen most clearly from Figs. 2 and 5, stationary jamb 24 has secured to the back surface thereof by any desirable means, such as screws or the like, a plurality of elongated brackets 36, preferably metallic, which are mounted thereto in longitudinally spaced relation. The brackets 36 are provided with an offset portion 38 which extends behind the rear surface of the movable jamb 26 in spaced relation thereto, said offset portion terminating in an inwardly extending flange 40. The flanges 40 extend into grooves 42 provided in the rear surface of the jamb 26.

Extending through jamb 26 from its front surface are a plurality of elongated studs 44. The studs 44 are threaded as at 46, their threaded ends extending through tapped holes 48 provided in the offset portion 38 of brackets 36. It will be understood that the holes 48 are in substantial alignment with the studs 44 whereby to threadedly receive the same. In order that studs 44 and movable jamb 26 may move as a unit, said studs are provided with slotted heads 50 which set in appropriate counterbores 52 provided in the jamb 26. Adjacent the rear surface of the jamb 26, stud 44 has extending therethrough a small pin 54 whereby it will be seen that jamb 26 is fixed to the stud 44 for inward and outward motion although said stud is freely rotatable. Washers 56 may be provided to aid in the secure gripping of jamb 26 by the head 50 and pin 54 of the stud.

Thus it will be seen that rotation of slotted head 50 by a screw driver or the like will result in sliding movement of the jamb 26 with respect to fixed bracket 36. The inwardly extending bracket flange 40 cooperates with the grooves 42 to act as guiding means for the movable jamb 26 and at the same time strengthens said jamb against an outward pull or thrust that may be imparted thereto should someone pull outwardly on the door when the latter is in its locked position. The fact that the grooves 42 are located intermediate the edges of jamb 26 is important and advantageous in that they are hidden from view, no matter what the position of jamb 26.

Intermediate the brackets 36, stationary jamb 24 and movable jamb 26 are provided with aligned, transversely extending slots 58 formed in the rear surface of the respective jambs. Seated within said slots 58 are elongated dowel members 60, preferably of square cross section. As will be seen most clearly in Fig. 6, slot 58 extends deeper in the movable jamb 26 to provide an excess portion 62 whereby said movable jamb may be adjusted in the manner aforescribed until the edge 64 of opening 62 comes into engagement with the fixed dowel 60. The dowel 60 may be secured to stationary jamb 24 in any suitable manner, such as by nailing, or said dowels may be secured directly to the outer house wall 32, if desired. The outer edges 68 of the dowels 60 provide means to which trim strip 20 may be mounted, and said outer edges extend slightly beyond the adjacent edge of jamb 26 whereby to provide a very small clearance between trim strip 20 and jamb 26, thus reducing bearing friction therebetween during movement of the latter, note Figs. 5 and 6. The dowels 60 are preferably of wood or the like whereby they are adapted to receive fastening elements, such as nails 70, which extend through trim strip 20. It will thus be seen that trim strip 20 is easily mounted in overlying relation with respect to the movable jamb 26 since fixed dowels 60 extend through said movable jamb to provide suitable anchoring means. If desired, trim strip 20 may also be fastened to inner house wall 34 by nailing or the like, such as shown at 72.

As will be seen most clearly from Fig. 3, threshold 22 abuts trim strip 20 whereby there is never any undesirable open space adjacent to the movable jamb no matter what

position the latter is in. In order to afford better weather-sealing characteristics, a fibrous pad 74 is secured to the bottom edge of movable jamb 26 to bridge the space between said jamb and threshold 22.

If desirable, metal bands or sleeves (not shown) may be used to encompass the dowels 60 in order to prevent spreading of said dowels when the fastening elements 70 are inserted therein. Also, to facilitate the entry of nails 70 into the end portion of the dowels 68, apertures 76 may be provided therein.

Thus it will be seen that there is provided in accordance with the invention an extremely simple yet efficient means for providing an adjustable jamb in a door frame structure. The instant invention does away with the laborious and time-consuming task of fitting doors within their frames when first hung, since by use of the instant construction, the door may be quickly mounted and then the adjustable jamb moved into its proper position. The instant invention is further characterized by the particular construction which affords maximum strength to the movable jamb and which prevents outward pulling of said jamb from its mounting. My construction also provides extremely effective guide means for the movement of the adjustable jamb in that the elongated dowels 60 will cooperate with slots 58 to always maintain said movable jamb in its proper vertical position while the inwardly extending flanges 40 serve to maintain the jamb 26 in proper alignment during the latter's in-and-out movement. The dowels 60 also provide effective means for receiving fastening elements whereby for the first time a trim strip covering the movable jamb may be mounted from the outside. In addition, the design of the instant construction provides maximum weathersealing characteristics.

While there is shown and described herein certain specific structure embodying the invention, it will be manifest to those skilled in the art that various modifications and rearrangements of the parts may be made without departing from the spirit and scope of the underlying inventive concept and that the same is not limited to the particular forms herein shown and described except insofar as indicated by the scope of the appended claims.

I claim:

1. In a door frame, a stationary jamb, a movable jamb adjacent thereto having a front face normally disposed in closely spaced relation with respect to the striking edge of a door, means for adjusting said movable jamb for varying the size of the door receiving opening defined thereby, said adjusting means comprising a fixed bracket extending from said stationary jamb in spaced relation to the rear face of said movable jamb, a longitudinally extending groove in said rear face spaced from the opposite longitudinal edges thereof, a flange carried by said bracket extending into said groove, an elongated stud extending through said movable jamb, said stud being freely rotatable with respect to said jamb but fixed thereto for longitudinal movement, said stud adjacent its inner end being threadedly received by said bracket whereby manipulation of the stud causes said movable jamb to move relative to said bracket, and a trim strip fixedly mounted in overlying relation with respect to the free outer side of said movable jamb.

2. In a door frame, a stationary jamb, a movable jamb adjacent thereto having a front face normally disposed in closely spaced relation within respect to the striking edge of a door, means for adjusting said movable jamb for varying the size of the door receiving opening defined thereby, said adjusting means comprising a plurality of longitudinally spaced brackets secured to and extending from said stationary jamb in spaced relation to the rear face of said movable jamb, said brackets each being provided with an inwardly extending flange, groove means in the rear face of said movable jamb spaced from the opposite longitudinal edges thereof for receiving said flanges, a plurality of elongated studs extending through said movable jamb, said studs being freely rotatable with

respect to said jamb but fixed thereto for longitudinal movement, said studs adjacent their inner ends each being threadedly received by one of said brackets whereby manipulation of the studs causes movement of said movable jamb relative to said bracket, said movable jamb further having a plurality of spaced transversely extending slots longitudinally staggered with respect to said brackets, and a plurality of fixed mounting elements each extending from said stationary jamb through a respective slot and terminating adjacent the outer edge of said movable jamb, said fixed elements and said slots cooperating to provide supporting means for said movable jamb throughout its normal range of adjustment, the outer edges of said fixed elements providing spaced supports of substantial depth for receiving fastening means to fixedly mount a trim strip over the outer edge of said movable jamb.

3. A door frame as set forth in claim 2 further characterized in that said fixed mounting element comprises an elongated dowel of square cross section.

4. A door frame as set forth in claim 2 further characterized in that said stationary jamb and said movable jamb have cooperating interengaging surfaces for providing a weatherseal therebetween.

5. A door frame as set forth in claim 2 further characterized in that there is provided a threshold which underlies said movable jamb, said movable jamb having secured to its lower edge a fibrous strip for providing weatherseal means between said movable jamb and said threshold.

6. In a door frame, a stationary jamb, a movable jamb adjacent thereto having a front face normally disposed in closely spaced relation with respect to the striking edge of a door, means for adjusting said movable jamb for varying the size of the door receiving opening defined there-

- by, said adjusting means comprising a plurality of longitudinally spaced brackets secured to and extending from said stationary jamb in spaced relation to the rear face of said movable jamb, said brackets each being provided with an inwardly extending flange, groove means in the rear face of said movable jamb spaced from the opposite longitudinal edges thereof for receiving said flanges, a plurality of elongated studs extending through said movable jamb, said studs being freely rotatable with respect to said jamb but fixed thereto for longitudinal movement, said studs adjacent their inner ends each being threadedly received by one of said brackets whereby manipulation of the studs causes movement of said movable jamb relative to said bracket, said movable jamb further having a plurality of spaced transversely extending slots longitudinally staggered with respect to said brackets, a plurality of fixed mounting elements each extending from said stationary jamb through a respective slot and terminating slightly beyond the outer edge of said movable jamb, said fixed elements and said slots cooperating to provide supporting means for said movable jamb throughout its normal range of adjustment, and a trim strip fixedly mounted in overlying relation with respect to the outer edge of said movable jamb, said trim strip having means for securing it to the outer ends of said mounting elements.
